UNITED STATES PATENT OFFICE

CLAUDE B. DAVIS, OF CHASE CITY, VIRGINIA, ASSIGNOR OF ONE-EIGHTH TO JAMES H. BURROUGHS, OF ASHEVILLE, NORTH CAROLINA, ONE-EIGHTH TO THOMAS E. PARNELL, OF CHATTANOOGA, TENNESSEE, AND ONE-EIGHTH TO ADAM TYREE FINCH, OF CHASE CITY, VIRGINIA.

CHEWING-GUM WRAPPER.

No. 884,800.

Specification of Letters Patent.

Patented April 14, 1908.

Application filed October 16, 1907. Serial No. 397,690.

To all whom it may concern:

Be it known that I, CLAUDE B. DAVIS, a citizen of the United States, residing at Chase City, in the county of Mecklenburg and 5 State of Virginia, have invented new and useful Improvements in Chewing-Gum Wrappers, of which the following is a specification.

This invention relates to wrappers for chewing gum and other commercial articles 10 sold in stick form, the object of the invention being to provide a one piece wrapper of suitable material adapted to be folded in such manner as to provide compartments or cells for the sticks and sealing flaps for the ends of 15 the package and also for the cells or compartments, whereby each stick of gum or other material is contained in separate compartment or cell all to itself and ample provision is made for printing the name of the manufacturer or dealer thereon or any other desired advertising matter. By means of the 20 wrapper hereinafter described, the use of tin foil or equivalent material may be dispensed with.

25 With the above and other objects in view the invention consists in the novel construction, combination and arrangement of parts hereinafter fully described, illustrated and claimed.

30 In the accompanying drawings, Figure 1 is a plan view of a wrapper embodying the present invention before the same is folded. Fig. 2 is a perspective view of the wrapper folded sufficiently to inclose the sticks of 35 chewing gum or other material. Fig. 3 is a longitudinal section through the package after the wrapper has been completely folded. Fig. 4 is a cross section through the same. Fig. 5 is a plan view similar to Fig. 1 40 showing the wrapper elongated as compared with Fig. 1, for a purpose which will appear. Fig. 6 is a perspective view of a partially made up package, the wrapper being folded with the exception of the sealing flaps. Fig. 45 Fig. 7 is a longitudinal section through the completely folded package. Fig. 8 is a cross section through the same.

The wrapper contemplated in this invention is cut by means of a die or in any suitable 50 manner from sheet material such as paper of any desired quality or texture, tin foil or thin sheet metal and may be said to comprise a main body portion or compartment flap 1,

end closing flaps 2 and 3 and a sealing flap 4 as clearly shown in Fig. 1. The end flaps 2 55 and 3 are gummed or coated adjacent to their outer extremities with adhesive material as indicated at 5 and a sealing flap 4 is likewise provided along its edge with gum or other adhesive material as indicated at 6. 60

The compartment flap 1 is indented along parallel lines as indicated at 7 or otherwise creased to facilitate folding said flap so as to provide compartments or cells in which the sticks 8 of chewing gum or other material are 65 placed in the manner illustrated in Figs. 2, 3 and 4. In other words, the compartment flap 1 is folded in the form of bellows, the sticks 8 being arranged alternately on opposite sides of the flap as clearly indicated in 70 Fig. 2. After the sticks are brought together in the relation to the wrapper as shown in Fig. 3, the end flaps 2 and 3 are folded around the ends of the package and pressed against the body of the package so as 75 to adhere thereto after which the final sealing flap 4 is folded transversely around the package and pressed against the same so as to adhere firmly thereto. The printed matter is arranged on the sealing flap 4 so that when 80 the package is completed, such printed matter will appear on the outside of the package, thus doing away with the necessity of an extra wrapper or lid.

If desired, the compartment flap 1 of the 85 wrapper may be made longer as shown in Fig. 5 so that a sufficient number of folds may be provided to permit all of the sticks 8 to be arranged on the same side of the compartment flap, there being a sufficient number of 90 fold lines 7 to provide the necessary number of cells or compartments on the same side of the wrapper. In all other respects, the wrapper illustrated in Figs. 5 to 8 inclusive is identical with the one illustrated in Figs. 1 to 95 4 inclusive.

As each stick of chewing gum or other material occupies an individual cell or compartment and is thoroughly protected thereby, it is unnecessary to use tin foil, paraffin paper 100 or the like in addition to the wrapper as is now the common practice, thus effecting a considerable saving in packaging chewing gum and other material sold in similar packages. It will be understood that the 105 wrappers may be cut out in large quantities by

suitable dies and likewise the fold lines 7 may be provided by suitable dies for that purpose.

Having thus fully described the invention, what is claimed as new is:—

- 5 1. A wrapper of sheet material for the purpose described comprising an oblong body creased on parallel lines to form compartments when folded, an end flap projecting laterally from one end of the body, another end flap projecting laterally from the opposite side of the body between the ends of the body, and a sealing flap forming an end extension of the body.
- 10 2. A wrapper of sheet material for the pur-

pose described comprising an oblong body 15 creased reversely on parallel lines to form bellows-like compartments when folded, end flap projecting laterally from one side of one end of the body, another end flap projecting laterally from the opposite side of the body 20 between the ends of the body, and a sealing flap forming an end extension of the body.

In testimony whereof I affix my signature in presence of two witnesses.

CLAUDE B. DAVIS.
